UNITED STATES PATENT OFFICE.

EUGENE B. CROCKER, OF PAWTUCKET, RHODE ISLAND.

NECKTIE-FASTENER.

SPECIFICATION forming part of Letters Patent No. 366,156, dated July 5, 1887.

Application filed July 8, 1886. Serial No. 207,397. (No model.)

To all whom it may concern:

Be it known that I, EUGENE B. CROCKER, of the city of Pawtucket, county of Providence, and State of Rhode Island, have invented certain new and useful Improvements in Necktie-Fasteners, of which the following is a full, clear, and exact description, reference being had to the accompanying drawings, forming part of this specification.

10 My invention relates to the devices known as "necktie-fasteners," which are designed to be attached to neckties or scarfs, in order to adjust and maintain the same in wearing position.

15 The objects of my invention are to provide a device of this character whereby the necktie may be easily and accurately adjusted in position, and whereby the necktie may be worn securely against displacement.

20 To the above purposes my invention consists in a fastening-cord secured to the necktie-shield by one end, and of a bite device, also secured upon the shield, and of a collar-button having a perforated shoe or other suitably-25 provided loosely-holding device for the fastening-cord to take through or about, all as hereinafter fully described and claimed.

In the accompanying drawings, illustrating my invention, Figure 1 represents a back view 30 of an ordinary form of necktie with my fastener shown connected therewith. The spring-bite is attached to the shield of the necktie, likewise the fastening-cord, which is passed through an eye in a collar-button, (shown un-35 attached,) and then passed through the bite for retention. Fig. 2 represents an enlarged side view of the novel form of collar-button used with my fastener, the button-head being shown in section. Fig. 3 represents an en-40 larged view of a modified form of my fastening collar-button, the head being in section. Fig. 4 represents an enlarged side perspective view of a further modified form of my securing form of collar-button. Fig. 5 represents a per-45 spective view of the wire spring-bite as used in my fastener.

In the said drawings like numbers of reference designate corresponding parts throughout.

50 Referring to the drawings, the ordinary form of necktie, 17, is provided with a suitable

shield, 13, to which the neckband of said necktie is secured, and which takes up about the collar and against the front collar-button of the wearer. To a point, 14, on shield 13 is firmly secured the cord or lace 15, provided with a rigid or metallic tip, 16, at the other or free end thereof. At a corresponding point to the point 14 is fixed the spring-bite 18. The point 14 and bite 18 are arranged at points 60 to one side of the center of the shield, as shown. The bite 18 for the fastening-cord 15 is formed of a piece of resilient wire bent on itself three times, as shown clearly in Fig. 5, so as to form a central loop, 10, and the sides 65 or arms 11, which are provided at the free ends with suitable tangs, 12, bent at an angle thereto and adapted to clinch and fasten into the material of the shield. The central loop, 10, of the W-shaped bite lies normally in the 70 same plane with the arms 11 thereof, and obviously, when the cord 15 is passed under the loop 10 and over each arm 11, as shown in Fig. 1, the device forms a secure bite for the cord. The collar-button 19 is formed of a saucer-shaped head, 7, to which is fixed the doubled wire or staple 8, formed into the post and shoe 9 of the button. 75

In the form shown in Fig. 2 the doubled wire 8 has the closed end bent into a narrow long loop 80 or eye, to form the perforated or eyed shoe 9 of the complete button, and the sides of the wire are bent in toward each other and constitute the post of the button. The free ends of the doubled wire are spread apart, as shown, and 85 fastened at opposite points on the circumference of the button-head 7. The shoe 9, post, and free ends of the doubled wire 8 all lie in the same plane, which is approximately normal to the plane of the button-head. However, in 90 order to throw the shoe 9 out of the plane of the other points of the doubled wire, as described, the sides of said wire forming the post of the button may be twisted on one another, and thereby turn the shoe into a different plane 95 from a button-hole.

In the modified form of Fig. 3 the shoe 9 is formed as above described; but the sides of the wire 8, forming the post, are made straight, 100 and are brought together side by side and fixed near a central point on the button-head

7. In this construction the plane of the two sides forming the post lies nearly at right angles to the plane of the shoe 9.

In Fig. 4 I have shown a still further modification, in which the doubled wire 8 has the closed end formed into a circular area to form the perforated shoe 9, and the sides forming the post are set together with the free ends flaring outwardly and secured at opposite points to the circumference of the button-head 7. The post stands obliquely to the button-head, and the shoe 9 is formed over about parallel with the button-head. The collar-button 19, having an eyed or perforated shoe, 9, is shown as threaded by the fastening-cord 15 and as in a free or unattached position. It is to be understood, however, that the collar-button 19 is arranged at the front of the neck of the wearer of the necktie, and is set through the button-holes of the shirt and collar, (not shown,) so that the open shoe 9 is disposed to the outside and abuts against the shield 13, in an obvious manner. It is now evident that by having the fixed cord 15 passed through shoe 9 of the collar-button, set in operative position, by drawing on said cord the necktie will be drawn snugly up against the collar and collar-button, and in this position the cord is then to be passed through the central loop of the bite 18, and thereby secured against slipping, so as to retain the necktie in the desired adjusted position.

In fastening devices for neckties it is desirable to have the device securely locked and retained in the collar-button of the wearer, so as to be held secure against dislodgment therefrom at all times while worn. With the ordinary form of a collar-button having a flat or disk-shaped shoe for holding the fastening device the accidental disengagement of said parts frequently occurs.

From the foregoing description it will be obvious that in the use of the button with a perforated shoe for holding the fastener the greatest certainty of security is provided, the virtues of which will at once commend the device to users.

I preferably use a non-elastic fastening-cord and arrange parts of the fastener as shown. However, it is evident that my invention may be variously modified without substantially departing from the spirit thereof, as herein described and claimed. For instance, another form of bite for the fastening-cord may be used as an equivalent for the one I show.

Having thus described my invention, I claim as new and desire to secure by Letters Patent—

1. The combination of the shield, a fastening-cord secured by one end to said shield, a

bite device fixed to said shield at a corresponding point to said cord, and a collar-button provided with a perforation or eye therein, said cord passed through said button-eye and bite, whereby the tension of the fastening-cord may be regulated to adjust the necktie. 65

2. The combination of the shield, a fastening-cord or lace secured at one end to said shield, a spring-acted bite fixed to said shield at a point corresponding to the fixed point of said cord, and a collar-button provided with a perforated shoe, said cord threaded through said perforation of the shoe and passed through the spring-bite, whereby the fixed point of the cord and the bite may alike be 70 drawn near the perforated shoe by pulling the cord in adjusting the necktie.

3. The combination of the shield, a fastening-cord provided at one end with a rigid tip and fixed at the other end to a point on said shield, a spring-bite consisting of a resilient wire bent three times on itself, somewhat W-shaped, the central loop of said wire forming a spring-bite with either or both sides or arms, and the free ends of said arms formed 85 with tangs to clinch in the shield, said bite secured by its tangs to the shield at a corresponding point to the fixed end of the cord, and a collar-button having a shoe with an eye therein, said cord passed through said eye 90 and under the central loop of said spring-bite, whereby the shield may be drawn up toward the collar-button by drawing on the cord for adjustment and may be held in any position by the bite. 95

4. The combination, with the button-head of the collar-button, of the doubled wire formed into a looped shoe at the closed end and the side strands thereof brought together, and having the free ends thereof bent outwardly and secured flatly upon the button-head and in the rim thereof, substantially as described, whereby a collar-button may be formed with a perforated shoe. 100

5. The combination of the shield 13, the fastening-cord 15, the collar-button having an eye or perforation therein, substantially as described, and the spring-bite 18, all arranged and constructed substantially as described. 105

6. The collar-button comprising the combination, with the button-head 7, of the doubled wire 8, formed into the looped shoe 9 and the shank and having the free ends thereof bent outwardly and secured to said head, substantially as herein described. 110
